UNITED STATES PATENT OFFICE.

NORBERT BURAS AND FRANK ADOLPH, JR., OF BOOTHVILLE, LOUISIANA.

FIRE-EXTINGUISHER.

1,191,560.

Specification of Letters Patent. Patented July 18, 1916.

Application filed September 30, 1915. Serial No. 53,420.

To all whom it may concern:

Be it known that we, NORBERT BURAS and FRANK ADOLPH, Jr., citizens of the United States, residing at Boothville, in the parish of Plaquemines and State of Louisiana, have invented new and useful Improvements in Fire-Extinguishers, of which the following is a specification.

Our present invention pertains to fire extinguishing means; and it contemplates the provision of a simple, quick-operating and efficient apparatus for isolating gasoline or other fuel oil from the carbureter of an internal combustion engine in the event of fire occurring in the carbureter, this with a view to cutting-off the supply of fuel and at the same time extinguishing the fire by the use of water.

With the foregoing in mind, the invention will be fully understood from the following description and claims when the same are read in connection with the drawing, accompanying and forming part of this specification, in which the figure is an elevation of the apparatus constituting the best practical embodiment of our invention that we have as yet devised.

In carrying out our invention in connection with a gasoline tank 1 and a carbureter 3 of an internal combustion engine, we interpose between the tank 1 and the carbureter 3 a pipe 2, valved at 4 and provided, by preference, above the valve 4 with a sight glass 11. We also provide a water tank 5 which in the preferred embodiment of our invention and for the sake of compactness is arranged in superimposed relation to the gasoline tank 1 as illustrated. From the tank 5 a pipe 6 extends downwardly and is connected to a receptacle 8 which, in turn, is connected through a pipe 9 with the beforementioned fuel-supply pipe 2. The pipe 6 is provided at 7 with a cut-off valve, and the receptacle 8 is provided 45 at its lowermost point with a drain cock 10.

In the event of fire occurring in the carbureter, the operator of the apparatus has but to fully open the normally-closed valve 7, whereupon a head of water will pass through the receptacle 8 and into the pipe 2. When the water occupies the portion of the pipe 2 adjacent to the carbureter, the gasoline or other oil being lighter than the water, retreats through the water to a position at the opposite side of the same, with

reference to the carbureter, and in this way the gasoline or other oil is isolated from the fire in the carbureter. It will also be manifest that at the same time a portion of the water will drench and tend to put out 60 the fire, and the water will also have the effect of forcing the gasoline or other oil back toward the tank 1, and when this end is accomplished, as can be readily ascertained through the sight glass 11, the valve 65 4 is closed with the result that the gasoline or other oil is cut off from the fire point.

When the fire is extinguished, the normally-closed valve 7 is closed to shut off the water, and then the normally-closed 70 drain cock 10 is opened to permit water to escape from the receptacle 8 and the portion of the pipe 2 between said receptacle and the valve 4, and then when the cock 10 is closed and the valve 4 is opened, the operation of the engine connected with the carbureter 2 can be reestablished.

Having described our invention, what we claim and desire to secure by Letters-Patent, is:

1. In means for extinguishing fire in an internal combustion engine, the combination with a fuel tank, a pipe leading from said tank to a part of the engine, and a valve arranged in said pipe at an intermediate 85 point in the length thereof; of a receptacle connected with said pipe at a point below the valve thereof and having a drain cock, a water tank elevated above the first-named pipe, and a valved pipe leading from the 90 water tank to the said receptacle.

2. In means for extinguishing fire in an internal combustion engine, the combination with a fuel tank, a pipe leading from said tank to a part of the engine, a valve arranged in said pipe, and a sight glass arranged in the pipe above said valve; of a water tank elevated above said pipe, and a valved-conduit leading from the water tank to the first-named pipe at a point below the 100 valve thereof.

In testimony whereof we have hereunto set our hands in presence of two subscribing witnesses.

NORBERT ^{his} X BURAS.
FRANK ADOLPH, Jr. ^{mark}
